UNITED STATES PATENT OFFICE.

THOMAS F. GAFNEY AND THOMAS C. DAWSON, OF LYNN, MASSACHUSETTS.

LEATHER-WORKING MACHINE.

SPECIFICATION forming part of Letters Patent No. 448,422, dated March 17, 1891.

Application filed December 22, 1890. Serial No. 375,424. (No model.)

To all whom it may concern:

Be it known that we, THOMAS F. GAFNEY, of Lynn, in the county of Essex and State of Massachusetts, a citizen of the United States, and THOMAS C. DAWSON, a subject of Victoria, Queen of Great Britain, &c., and now residing in said Lynn, have invented a new and useful Improvement in Leather-Working Machines, of which the following is a full, clear, and exact description, reference being had to the accompanying drawings, forming a part of this specification, in explaining its nature.

The invention relates to a machine for slicking, rubbing in, and finishing leather, the nature of which is best ascertained by the following description and the drawings.

In the drawings, Figure 1 is a view in side elevation of a machine having the features of our invention. Fig. 2 is a view, partly in side elevation and partly in vertical section, further illustrating the machine. Fig. 3 is a view in vertical section from side to side of the machine, taken through the rubbing-tool and parts in immediate conjunction thereto. Fig. 4 is a detail view enlarged of the rubbing-tool, a flexible bed, and the reciprocating bed support or roll, showing the position they occupy at or near the back end of the stroke. Fig. 5 is a detail view in section showing the carriage for carrying the reciprocating bed support or roll.

A is the frame of the machine. It preferably is made of wood and comprises the rear uprights $a a'$, which support the power-shaft a^2 and the shaft a^3 and the uprights $a^4 a^5$, which are secured or joined to the uprights $a a'$ by upper and lower tie-pieces $a^6 a^7$, the lower tie-pieces a^7 also acting as the bed or foundation piece of the frame. The uprights $a^4 a^5$ are braced by the bracing-rod $a^8 a^9$, preferably extending from the sides of the uprights to floor-beams above. From the uprights $a^4 a^5$ there extend horizontal side pieces $a^{10} a^{11}$. These horizontal side pieces are joined at their inner ends to the uprights $a^4 a^5$, and said pieces a^{10} are supported at their outer ends by the uprights a^{12} . (See Fig. 1.) They furnish or provide supports for the rails upon which the traveling or reciprocating bed support or roll, hereinafter described, slides, and they also form a space or recess in which is located a flexible bed, the surface

of which is carried flush with or a trifle above the upper surfaces of the side pieces by the bed-supporting roll. There is also secured to 55 one of the side pieces by brackets $a^{13} a^{14}$ a supplementary or auxiliary bed a^{15} , preferably not made of wood. (See Fig. 5.) The shaft a^{16} supports at one end a crank-gear B and has between the uprights $a a'$ the fast and 60 loose pulleys $b b'$, Fig. 3. The shaft a^{17} carries at its end the crank-gear B', which meshes with the crank-gear B. The gear B has the crank-pin c , which is connected with the hinged or pivoted tool-holder c' by the pitman 65 c^2 . The gear B' has a crank-pin c^3 , which is connected with the sliding block or carriage c^4 , supporting the hinged bed support or roll c^5 , by the pitman c^6 . The hinged bed support or roll c^5 is connected with the pitman c^6 by 70 the rod c^7 . This connection provides the hinged bed support or roll with the swinging movement in relation to its carriage, the object of which will be hereinafter described.

C is the rubbing - tool. It preferably is 75 made of fibrous material like canvas or carpet formed into the shape of a pad and filled with an absorbent filling. It is secured in any convenient or desirable way to the lower end of the tool-holder c' , and it is supplied 80 with any liquid composition which it is desired to rub into the leather by the flexible supply-pipe D, which extends through a hole in the tool-holder and discharges or opens into the interior of the rubbing-tool at d . The 85 pipe is connected with a feed-can d' , supported by the frame, and has a cock d^2 , by which the feed of the liquid is controlled. The tool-holder c' is attached at e to the end of the pitman c^2 . It is pivoted to the lower 90 end of the swinging bar e' by a pivot e^2 , passing through the forked upper end and the lower end of the swinging bar. The swinging bar e' is pivoted at e^3 to the swinging-bar supports e^4 , there being two of these supports, 95 one upon each side of the bar e' . The swinging bar e' is connected with the bar-supports by a pivot, which extends through holes in the upper ends of both supports and the bar. The bar-supports e^4 are pivoted at their lower 100 ends e^5 to the frame-extension e^6 . The upper end of the swinging bar e' is held to the section e^7 of the frame-extension by the cross-pin e^8 , extending through a slot e^9 in the up-

per end of the swinging bar. This fixes or holds the upper end of the swinging bar, while it permits the bar to rise and fall when it is moved or swung. The frame-extension 5 e^6 is made up of the lower side pieces $e^{10} e^{11}$, the upper side piece e^{12} , the tie-piece e^7 , and the end piece e^{13} , and the swinging bar e' and bar-supports e^4 are arranged to move between the side pieces $e^{10} e^{11}$. (See Fig. 3.) The gears 10 B B' are supported at a height to cause the pitmen $c^2 c^6$ to act to hold the tool-support and the bed support or roll in a perpendicular or vertical position during very nearly their entire forward or operating movement 15 and to incline them during their reverse or backward movement.

The leather, skin, or other material under treatment is supported upon a flexible bed F, preferably of leather, attached to the frame 20 at its front and rear ends and held by its front and rear ends only to be substantially flush with the upper edges of the side pieces $a^{10} a^{11}$ and between them. It is held or sustained against the wiping or slicking action 25 of the rubbing-tool C by the bed support or roll G. This roll is mounted upon the hinged support c^5 , which is pivoted at g to the slide c^4 . The slide is mounted upon the yielding ways or rails g' upon the inside of the side 30 pieces $a^{10} a^{11}$.

The slide or carriage c^4 is represented as composed of side sections g^2 , which are held separate from each other by the cross-pieces $g^3 g^4$, the ends of the pieces g^3 extending beyond the outer sides of the pieces g^2 and resting upon the upper surfaces of the rails g' , and the ends of the cross-pieces g^4 extending beyond the outer sides of the pieces g^2 and bearing against the under surfaces of the 40 rails g' . The rails g' are connected at their ends by forked connecting-pieces G' , which are mounted respectively upon the springs $g^5 g^6$, carried by the rods $g^7 g^8$. The springs may be adjusted upon the rods or by means 45 of suitable adjusting-nuts to vary their tension, or the rods themselves may be adjusted by screwing into nuts. We have represented the last-named construction, the rods screwing into the nuts $g^9 g^{10}$, respectively, and having the wheels g^{11} , by which they are turned. As the rails are thus held between the two side pieces $a^{10} a^{11}$ of the frame upon springs, it follows that they permit a yielding movement to the flexible bed, the bed support or 50 roll, and its carriage. The rails are vertically adjustable not only for the purpose of varying the power or stress with which the work is held in contact with the rubbing-tool, but to also vary the operative position of the flexible bed and its supporting-roll in relation to the rubbing-tool for the purpose of taking leather or skins varying in thickness. The rod g^8 is carried by a lever h . This lever is pivoted at h' and is held elevated by the 55 spring h^2 . It is moved downward in opposition to the spring to engage a latch h^3 , when the machine is not at work, for the purpose

of lowering the flexible bed sufficient to remove it from contact with the rubbing-pad.

There may be used in connection with the rubbing-tool and carried by the tool-holder c' or the end of the pitman c^2 an auxiliary rubbing or polishing tool M. This is represented as attached to the end of the pitman by the upright m and horizontal piece m' . This 75 brings this auxiliary rubbing-tool in operative relation with the supplementary bed a^{15} . Its use is to finish or polish that portion of the leather or skin which has been subjected to the action of the rubbing-tool and simultaneously with it.

At the beginning of the operation of the machine the rubbing-tool and the bed support or roll and the pad and the operating cranks and pitmen occupy the position represented in the position in Fig. 1—that is, the rubbing-tool is held in inclined position and lifted from the bed. The hide or skin is then placed upon the bed and upon the starting of the machine the rubbing-tool is moved downward upon it into position over the bed roll or support, and the bed roll or support is moved and held in a vertical position and moves in unison with the rubbing-tool through its forward or working stroke and 95 a peculiar rubbing or slicking action is thus given the rubbing-tool. Upon the reverse movements of the stroke the rubbing-tool bed and bed roll or support take the position represented in Fig. 1, and are held in that position during the full backward stroke—that is, the rubbing-tool is held from contact with the leather or other material carried by the bed.

While this machine is especially adapted 105 for doing that part of leather-working known as "seasoning," yet we do not intend to confine its use to such work, as it may be employed in the other branches of leather working or finishing without departing from the 110 spirit of the invention.

Having thus fully described our invention, we claim and desire to secure by Letters Patent of the United States—

1. The combination, in a machine of the 115 character specified, of the flexible bed F, its traversing yielding bed support or roll G, and the reciprocating tool C, having the forward and backward movement in relation to the bed support or roll specified, as and for 120 the purposes described.

2. The combination, in a machine of the character specified, of the flexible bed F, the hinged bed support or roll G, its carriage c^4 , the crank c^3 , pitman c^6 , connecting the crank 125 with the carriage c^4 , the rod c^7 , connecting the pitman with the hinged roll-support c^5 , with the reciprocating tool C, its support c' , hinged to a swinging bar e' , held at its upper end, as specified, its pivoted supports e^4 , the crank c , 130 and the pitman c^2 , connecting the crank with the hinged tool-support, substantially as described.

3. The combination of the vibrating tool

- C, having the movements specified, the flexible bed F, the traveling bed support or roll G, the roll-carriage c^4 , and yielding ways for the same, substantially as described.
- 5 4. The combination of the vibrating tool C, having the movements specified, the flexible bed F, the yielding bed-supporting roll G, and the traversing yielding bed supporting the roll G, substantially as described.
- 10 5. The combination of the vibrating rubbing-tool C, having the movements specified, the flexible bed F, and the adjustable bed-supporting roll G, substantially as described.
6. The combination of the vibrating tool
- 15 C, having the movements specified, the flexible bed F, the traversing bed-supporting roll G, and the lever for depressing said roll, substantially as described.
7. The combination of the vibrating tool
- C, having the movements specified, the flexible bed F, the traversing bed-supporting roll G, and the lever for depressing said roll, and the latch for locking or holding the lever and roll depressed, substantially as described.
8. The combination of the vibrating tool C, having the movements specified, the flexible bed F, the supplementary bed a^{15} , the traveling bed-supporting roll G, and the auxiliary rubbing or finishing tool M, having the movements of the vibrating tool C and connected therewith or with its operating mechanism, as and for the purposes described.

THOMAS F. GAFNEY.
THOMAS C. DAWSON.
